(57) **CLAIM**

I claim the ornamental design for a frame, as shown and described.

DESCRIPTION

FIG. 1 is a front plan view of a frame showing my new design;

FIG. 2 is a partial sectional side view on an enlarged scale of the frame seen along arrows 2—2 in FIG. 1;

FIG. 3 is a rear plan view of the frame shown in FIG. 1;
FIG. 4 is a front perspective view of the frame shown in FIG. 1; and,

FIG. 5 is a rear perspective view of the frame shown in FIG. 1.
